Inventor
Sidney S. Smith
By Frank E. Liverance, Jr.
Attorney

UNITED STATES PATENT OFFICE.

SIDNEY S. SMITH, OF GRAND RAPIDS, MICHIGAN.

ADJUSTABLE MOUTHPIECE.

Application filed March 17, 1923. Serial No. 625,691.

To all whom it may concern:

Be it known that I, SIDNEY S. SMITH, a citizen of the United States of America, residing at Grand Rapids, in the county of Kent and State of Michigan, have invented certain new and useful Improvements in Adjustable Mouthpieces; and I do hereby declare the following to be a full, clear, and exact description of the invention, such as will enable others skilled in the art to which it appertains to make and use the same.

This invention relates to an adjustable mouth piece for wind instruments such as cornets, trombones, various types of horns and the like. It is a primary object and purpose of the present invention to make a mouth piece wherein the lip engaging portion thereof may be adjusted to any desired position with respect to the remainder of the said mouth piece, and either secured in said adjusted position or left free to move so that the performer may change position as desired during the performance of the selection played. To this end I have made the constructions illustrated in the accompanying drawing, in which,

Fig. 1 is a longitudinal section centrally of a preferred construction of mouth piece made in accordance with the invention.

Fig. 2 is a like view of a modified form of construction of mouth piece, and

Fig. 3 is a somewhat reduced side elevation of the mouth piece shown in Fig. 1.

Like reference characters refer to like parts in the different figures of the drawing.

In the construction of the preferred form, shown in Fig. 1, an elongated member 1 of suitable metal is used, at one end being enlarged, as indicated at 2 and formed adjacent its end with curved surfaces 3, said surfaces being curved substantially in arcs of a sphere. Through the member 1 a longitudinal opening 4 is made which is tapering and reduces in size from what may be termed the inner end of the member to the head or enlargement 2 thereof, thence flaring outwardly and enlarging in the end of the enlarged portion 2, as shown at 5.

A ring 6 of metal is formed on its inner sides with curved surfaces 7 conforming to the surfaces 3 heretofore described so that the ring 6 may have a universal angular movement with respect to the longitudinal axis of the member 1 and may be adjusted to an indefinite number of positions on the enlarged head 2 thereof. If desired, the ring

may be secured in any preferred position to which adjusted, a screw 8 being threaded through an opening in the ring 6 so that its inner end may be brought to bear against the surface at 3 to secure the parts against relative movement. This securing of the ring against movement is not necessary unless desired as the screw 8 may be left in inoperative position if desired.

With this construction, it is evident that the ring 6 with which the lips engage may be adjusted for the particular performer and with the screw 8 left in inoperative position, the position of the lip engaging ring may be changed as may be desired during the operation of the instrument with which the mouth piece is used. This dispenses with the absolute rigidity present in solid non-adjustable mouth pieces and is of value in ease of operation and automatic correction of the mouth piece to the lips during the operation without detriment to the quality of music produced.

In Fig. 2, a modified form of structure is shown, the elongated member 9 having a somewhat enlarged end 10 on the inner sides of which a socket 11 is made having surfaces of arcs of a sphere. The regular form of mouth piece now almost universally used, indicated at 12, is equipped with a member 13 having surfaces which conform to the inner surfaces of the socket 11 whereby a universal movement of the immediate mouth-piece member 12 with respect to the member 9 is permitted, there being in effect a ball and socket joint made. A projection 14 at the inner side of the member 13 has an opening therethrough which communicates with the enlargement made to fit the lips on the inner sides of the member 12. A flexible member 15 of rubber or like material is attached at one end to the projection 14 and lies within and lengthwise of the member 9, as shown, being connected thereto. The opening made lengthwise through member 15 is tapered, enlarging from the point of connection to the projection 14 to the end of the member.

This modified construction is also adjustable in that the lip engaging member 12 may be turned to any desired angle. The set screw 8 is not shown in the structure illustrated in Fig. 2, but it is obvious that it may be added if desired. This structure while not preferred, is capable of the desired adjustment, as is evident. It will be noted that

an annular recess is formed where the curved surface 7 of the ring 6 overhangs the outer end of the member 1. This has been found to add to the tonal qualities of the mouth piece. Other modifications in structure may be made without changing the invention, and all such as come within the scope of the appended claims defining the invention are to be considered as comprehended by the invention.

I claim:

1. In a device of the class described, an elongated member having a passage therethrough, and a member mounted thereon for angular adjustment with respect to the longitudinal axis of said member, said member being shaped for engagement by the lips, substantially as described.
2. In a device of the class described, an elongated member having a passage therethrough, and a member mounted at one end thereof for universal angular adjustment with respect to the longitudinal axis of said member, said member being shaped at its free end for engagement by the lips, substantially as described.
3. A mouth piece, comprising an elongated stem having a passage longitudinally therethrough, and a member mounted at one end of the stem for universal angular movement with respect to the longitudinal axis of the said elongated member, said

member being shaped at its free end for engagement by the lips and means for securing said member in any position to which it is adjusted.

4. A mouthpiece, comprising an elongated stem having a passage longitudinally therethrough and formed with an enlargement at one end, the opening being enlarged at said end of the stem, and said enlargement being curved at its outer side in the arc of a sphere, and a ring connected to the same and having its inner sides curved to conform to the said enlargement at the end of the stem so as to be universally adjustable thereon.

5. In a mouthpiece, a stem with a longitudinal opening therethrough, and a member adapted to be engaged by the lips adjustably mounted at one end of the stem to adjust to different positions substantially as described.

6. A mouth piece for wind instruments comprising an elongated member having a longitudinal opening therethrough, the outer end of said member having a curved surface, and a lip engaging member having an inner curved surface to embrace the curved surface of the elongated member, said lip engaging member overhanging said elongated member to form an annular recess.

In testimony whereof I affix my signature.
SIDNEY S. SMITH.
